UNITED STATES PATENT OFFICE.

GUY W. FERDON, OF CRESSKILL, NEW JERSEY.

JAR-LIFTER.

1,266,112.

Specification of Letters Patent. Patented May 14, 1918.

Application filed August 16, 1917. Serial No. 186,482.

To all whom it may concern:

Be it known that I, GUY W. FERDON, a citizen of the United States, residing at Cresskill, county of Bergen, State of New

5 Jersey, have invented certain new and useful Improvements in Jar-Lifters; and I do hereby declare the following to be a full, clear, and exact description of the invention, such as will enable others skilled in 10 the art to which it appertains to make and use the same.

My invention relates to improvements in jar lifters, and is especially designed for lifting jars of fruit or other food products 15 which are to be sterilized or canned or "put up", into or out of boiling water or other sterilizing agent.

In the operation of canning, particularly when performed in the ordinary domestic 20 kitchen, it is common to heat a number of jars; that is, to have them immersed up to their necks in boiling water while the fruit to be preserved is put in them and cooked or sterilized in such receptacles, which 25 are sealed while the contents are still hot, and thus are preserved in sterile air-tight condition.

It is necessary to lift these jars out while 30 they are still hot. Various frames for holding a number of jars have been invented, but my invention is a clamp or device which is handy and dependable, and can be used to lift out a single jar at a time without danger to the jar or to the operator, and 35 with the greatest ease. It is simple, cheap and effective; and will fit most all the jars in common use for canning purposes, as well as clamp and withdraw the ordinary tin can, used by some instead of glass jars.

40 In the drawings:

Figure 1 is a view showing the device attached to a jar;

Fig. 2 is a perspective view of my improved lifter;

45 Fig. 3 is a perspective showing my device as used on a jar having a wire clamp; and

Fig. 4 is a perspective of a slightly modified form of my device.

In the drawings, the numeral 1 indicates 50 my jar lifter as a whole. This consists of a continuous wire bent as shown into two strands, having a handle 2 with a loop 3 at the top, and bent to horizontally forwardly projecting narrowing parts 4. The 55 wires are here bent to form the clamping jaws 5 at a suitable angle to the plane of

the handle. This angle is generally a right angle. The part 4 offsets the handle so that a slight leverage is afforded in removing the lifter from a jar. 60

These jaws are bent to about the curvature of the neck of an ordinary preserving jar, say, of the Mason type, such jars being usually provided with a bead or groove below the threaded part; but the lifter will 65 also work on those jars which have a wire device for clamping down the glass top.

The ends of the jaws preferably do not come quite together, leaving an opening 6, though this opening may be closed. I may 70 also provide an adjustable clamp, and I may insert a coil, indicated at the dotted lines at 8, at the turn of the handles. The ends of the jaws 5 may terminate in upwardly or outwardly bent curved portions 75 9, as shown. As seen in Fig. 4, these may be omitted.

My device is made of a single piece of rather heavy wire, say wire of 8 or 10 gage, and stiff enough when bent to hold a full 80 jar without danger. The bend of the loop may be made more sharp and the clamping action thus increased. The hand and all fingers of the operator, or finger and thumb, may assist the clamping action. I 85 prefer to have the clamp firm enough to hold the jar, yet sufficiently loose to yield to a sharp pull, leaving the jar in place.

I prefer to have the ends of the handle or upright part quite close, so that a finger 90 of the operator may be thrust between to spread them as indicated at 12.

I may also use my clamp to suspend a jar from a nail, either for storage or to serve for a transient container. I have indicated such a nail at 13. A pint jar thus arranged near a gas stove makes a safe and excellent receiver for burnt matches. For campers, too, this affords an excellent means for suspending food-stuffs, liquids, etc., out 100 of the way of insects or marauding animals. I may use two of my lifters, the second indicated at 14 in dotted lines, and this may serve as a means for suspending a jar to be used, say, as a well bucket. 105

My device is capable of many uses, but its primary use is that of a jar lifter. In using the device for this purpose, I thrust the clamp part smartly down over the top of a fruit jar. The clamps snap into place. 110 I may leave it as long as I please. I lift the jar out when I am ready, by grasping

firmly the upper portion of the handle, pinching it together as far as may be necessary to make a firm clamp on the neck of the jar; and release the device by giving a 5 quick tug and twist, these operations being assisted, if need be, by the finger of the operator in the manner indicated.

What I claim as new, and desire to secure by Letters Patent of the United States is:

- 10 1. In a jar lifter, in combination, a vertically arranged handle consisting of two strands of wire, an elastic loop connecting said strands and forming the upper part of said handle, the lower ends of said strands 15 forming the lower part of said handle being angularly inclined and approaching each other, offset portions extending forward from the lower end of said handle, and forming continuations of the said strands, 20 said parts so extending forward being substantially parallel and horizontal, and forwardly extending curved clamping jaws forming continuations of said forwardly extending portions the clamping effect being 25 referable to the loop.

2. In a jar lifter, in combination, a vertically arranged handle consisting of two strands of wire, an elastic loop connecting said wires and forming the upper part of 30 said handle, the lower ends of said strands forming the lower part of said handle being angularly inclined and approaching each other, offset portions extending forward from said handle, and forming continuations of said strands, said parts so extending forward being substantially parallel and horizontal, forwardly extending curved 35 jaws forming continuations of said forwardly extending portions, said jaws terminating near each other in upturned parts, 40 the clamping action being referable to the loop.

3. A jar lifter consisting of a single piece of elastic wire bent in two strands to form 45 an upright spring handle, the lower parts of said handle being inclined to each other slightly and approaching each other closer than the width of a finger, a continuation of

said strands forming parallel horizontal extensions and semicircular jar clamping jaws, 50 adapted to clamp the neck of a jar under pressure of said elastic handle and to be released by finger pressure within said handle.

4. In a jar lifter, in combination, a vertically arranged handle consisting of two 55 strands of wire, an elastic loop connecting said strands and forming the upper part of said handle, the lower ends of said strands forming the lower part of said handle being angularly inclined and approaching each 60 other, offset portions extending forward from said handle, and forming continuations of the said strands, said parts so extending forward being substantially parallel and horizontal, and forwardly extending 65 curved jaws forming continuations of said forwardly extending portions.

5. In a jar lifter, in combination, a vertically arranged handle consisting of two strands of wire, an elastic loop connecting 70 said wires and forming the upper part of said handle, the lower ends of said strands forming the lower part of said handle being angularly inclined and approaching each other, offset portions extending forward 75 from said handle, and forming continuations of said strands, said parts so extending forward being substantially parallel and horizontal, forwardly extending curved 80 jaws forming continuations of said forwardly extending portions, said clamps terminating near each other in upturned parts.

6. A jar lifter consisting of a single piece of elastic wire bent in two strands to form an upright spring handle, the lower parts of 85 said handle being inclined to each other slightly and approaching each other closer than the width of a finger, the continuation of said strands forming parallel horizontal extensions and semicircular jar clamping 90 jaws, adapted to clamp the neck of a jar under pressure of said elastic handle and to be released by finger pressure within said handle.

In testimony whereof, I affix my signature. 95
GUY W. FERDON.
